Inventor:

Henry Cogswell

UNITED STATES PATENT OFFICE.

HENRY COGSWELL, OF GREENWICH, NEW YORK.

HAME.

Specification of Letters Patent No. 22,937, dated February 15, 1859.

To all whom it may concern:

Be it known that I, HENRY COGSWELL, of the town of Greenwich, county of Washington and State of New York, have invented a new 5 and Improved Mode of Adjusting, Shifting, and Changing the Draft of Hames; and I do hereby declare that the following is a full and exact description thereof, reference being had to the accompanying drawings and to the letters of reference marked 10 thereon.

The nature of my invention consists in applying to the "eye"; (which is now used for the purpose of holding the draft tug; and 15 which is at present fastened to the hame) a movable slide—so constructed, that the "eye" and slide shall form a solid piece—which slide, by means of a screw, can be so raised or lowered upon the hame as to 20 change the point of draft to any desired position. Such slide is so constructed as to be made applicable to hames used for light or heavy draft, single or double.

To enable others skilled in the art to make 25 and use my invention, I will proceed to describe its construction and operation.

For carriage or light draft I construct the "eye" of the same materials now used, and adapt my invention to hames of wood or 30 iron; and in their usual form or make.

In order to change the point of draft I attach to the "eye" a slide, made of iron, or other proper materials—the "eye" and slide being cast together—which slide clasps the 35 hame. (Said slide is marked "A" in the accompanying perspective drawing No. 1). For the purpose of allowing the slide "A" to work up and down upon the hame, without projecting beyond the inner side of the 40 same a channel is cut in the hame; of the length, in which it is desired the slide shall work; so that the inner surface of the slide, is even, with the surface of the hame upon the inner side, or side where the hame rests 45 against the collar.

In the center of the slide "A" a hole is made, through which, the screw, (marked "B" in the accompanying drawing No. 1) passes (which is intended to be a screw with 50 a flat head).

Upon the outer surface of the hame, holes are made; at the desired distance; within the limit of the channel, over which the slide passes; (which holes are marked "C" in the accompanying drawing No. 1) which holes 55 are intended to receive the screw "B"; by the means of which the "slide eye" will be held, in the desired position.

In case of the application of my invention to hames, used for "common team" or 60 "heavy draft" I construct my eye and slide of the same material and make no change in the hame. I change however, the construction of the slide; (which is also marked "A" in the accompanying perspective drawing 65 No. 2) by causing a flange to project from the upper side of the slide; through which flange, a hole is made, for the purpose of allowing the screw; (marked "B" in the accompanying drawings) to pass into 70 the hame. The hame is channeled in the same manner as described in the light draft hame—the holes, however, which are made in the hame; for the purpose of holding the screw "B"; instead of being made along 75 the outer surface of the hame; as in drawing No. 1; are made along the back edge of the hame, at desired distances—within the distance over which the slide "A" passes—into which holes, the screw "B" passes through 80 the flange, for the purpose of holding the slide. The flange is projected above the slide, for the purpose of allowing the ring (which is marked "C" in the accompanying drawings; and which is now in use for the 85 purpose of holding the pole straps, of the hames;) to be fastened in the most convenient position in the center of the slide "A".

What I claim as my invention; and desire 90 to secure by Letters Patent is—

The application of the shifting slide, to hames, as they are now used; by means of which slide, the point and position of the draft of the hames, can be altered as desired. 95

HENRY COGSWELL.
